LIGHT DIMMER

Walter J. Penney, West Haven, Conn.

Application July 30, 1932. Serial No. 626,966

3 Claims. (Cl. 246--48.6)

My invention relates to improvements in light dimmers.

In my co-pending application, Serial No. 581,216, filed December 15, 1931, I have disclosed a light shield or dimmer of the type particularly applicable for use with the headlights of vehicles. My present invention is an improvement over that type of dimmer and consists of the particular spacing or disposition of the holding members 10 or fingers with which the shield is provided whereby the shield may be most advantageously positioned to intersect and deflect the undesirable rays emanating from the bulb to which it is attached.

15 A further important improvement manifest in my present invention resides in the provision and particular positioning of the holding members which cooperate with the annular grooves or depressions of a conventional light bulb to maintain the shield in adjusted position on the bulb and eliminate the possibility of the shield coming out of adjustment or working loose due to vibration or jar of the vehicle to which it is attached.

20 Other objects will be in part obvious from the annexed drawing and in part hereinafter indicated in connection therewith by the following analysis of this invention.

This invention accordingly consists in the features of construction, combination of parts and in the unique relation of the members and in the relative proportioning and disposition thereof, all as more completely outlined herein.

To enable others skilled in the art to fully comprehend the underlying features thereof that they may embody the same by the numerous modifications in structure and relation contemplated by this invention, a drawing depicting a preferred form of the invention has been annexed 35 as part of this disclosure, and in such drawing, like characters of reference denote corresponding parts throughout all of the views, of which—

Fig. 1 illustrates my device used in connection with a conventional vehicle headlight system;

40 Fig. 2 is a top view of my shield, illustrating the manner in which it is applied to a light bulb; Fig. 3 is a side view of my shield;

Fig. 4 is a front view of the shell;

50 Fig. 5 is a sectional detail view showing the seating relation of the rivet heads; and

Fig. 6 illustrates a modification thereof.

In the drawing, wherein for the purpose of illustration is shown a preferred embodiment of my invention, the numeral 5 designates a shell 55 which may be of any suitable material, but preferably of some light and highly resilient metal, such as spring steel, and sufficiently thin to eliminate breakage of the light bulbs 6 to which they are adapted to be applied, by reason of excessive weight. The inner surface 7 of the shell or disc

5 is highly polished or coated with a substance such as nickel or silver capable of efficiently reflecting light rays. The shell 5 is stamped or otherwise formed concave or semi-globular in shape to conform substantially to the contour of a bulb 6 with which it is associated, thus to shield or dim the rays of light emanating therefrom. While it will be understood that the shell 5 may be of any desired size, it has been found more practical and conducive to better results if its area is sufficient to substantially cover the end portion of the bulb 6 to its greater diameter, thus providing adequate interception area and a greater reflecting surface, the object of which will be later made apparent.

75 Disposed about the shell 5 in the relation shown, and to be described hereinafter, are tapered holding members or fingers 8, 9, 10 and 11, respectively. These fingers follow substantially the contour of the lamp 6 in such relation 80 as to insure ample gripping action and are of sufficient length to retain the device on the lamp as well as permitting a substantially universal adjustment about the globular part or bulge thereof. These fingers are preferably of tempered spring metal, as disclosed in my co-pending application, to better enable them to grip the bulb to hold the shield in adjusted position 85 thereon. The fingers may be either integral with the shell or shield 5 as shown in the modification illustrated in Fig. 6 or attached to the shell by rivets 13 as shown in Figs. 2 and 3. In the latter case, when rivets are used, the rivets 13 extend through the shell and through the respective fingers, each of the ends extending 90 through the shell and adjacent the inner surface 95 of the shell being provided with heads 14.

The conventional headlight bulb 6 is provided near its tip portion with a series of annular adjacent depressions or grooves 15, 16, 17, the depressions or grooves being spaced by intermediate annular ridges or bulges 18, 19, as indicated in Fig. 3. According to my invention, I make use of such depressions and ridges of the bulb to mount the shield on the bulb in a preferred 100 position and at the same time to prevent unintentional displacement of the shield from such preferred position due to vibration or related causes. Thus the rivets 13 secure the fingers to the shell while heads 14 of the rivets are so arranged as to define the preferred position of the shield by seating in a definite annular depression or groove of the bulb, with the edge of the shield engaging the side of a ridge or bulge between the grooves, whereby the shield 110 is substantially anchored in its position so defined.

115 In attaching the fingers to the shell 5, it will be seen upon reference to Figs. 2 and 3 of the drawing that the fingers 8 and 9 are spaced a 120

greater distance apart than are fingers 8 and 11, 9 and 10, or 10 and 11, respectively. These fingers are intentionally so spaced in order that the shield may be more readily positioned or tilted to 5 the position shown in the drawing to better reflect the rays emanating from the bulb upwardly against the upper rear portion of the headlight reflector. When the shield is tilted as shown in Figs. 2 and 3, the upper portion 10 thereof is adjacent the greater bulge of the bulb, while the lower portion of the shield is nearer the neck of the bulb where the bulge is not so pronounced. By thus spacing fingers 8 and 9 as above described, the top edge of the shield 15 may clear the greater bulge portion so as to engage against the side of the outermost ridge 19.

Referring to Figs. 2 and 3, the heads 14 associated with the fingers 8 and 9, respectively, 20 are positioned near the rim or edge of the shield 5 and the heads 14 associated with fingers 10 and 11 are set a greater distance from the edge of the shield. This purposeful positioning of the heads permits the heads 14 of the upper fingers 8 and 9 to seat in the annular groove 16 and the heads 14 of the lower fingers 10 and 11 to seat in the next or innermost groove 15, as 25 shown in Fig. 3, when the shield is in its adjusted position upon the bulb. Thus the top edge 30 of the shield is held against the sides of the outermost ridge of the bulb. When the shell is placed in this adjusted position, namely, with the heads 14 seating in grooves 15 and 16, respectively, and the top edge of the shield is 35 against the ridge 19, it is substantially impossible for the same to be dislodged or to come out of adjustment even by extreme vibration or jar to which it may be subjected.

In the modification shown in Fig. 6, the rivets 40 have been omitted and the fingers 21 are made integral with the shield 5a. In this case projections 22 are formed, by punching or otherwise, upon the interior of the shell 5a and in the same relation as are the heads 14 in Figs. 2 and 3. 45 These projections 22 are adapted to accomplish the same purposes as are the heads described in connection with Figs. 2 and 3.

In operation it will be seen upon reference to Fig. 1 and as described in my co-pending application above referred to that the device may be positioned on the bulb 6 in various positions of adjustment, one of which is shown. In such a placement the shell intercepts substantially all 50 of the direct rays from the bulb 6 while at the same time causing the intercepted rays to be reflected and diffused through the medium of the reflecting surface 7 and the reflector 25 in the head lamp casing 26. Obviously, also, the shell 5 aids to intercept the rays reflected by the reflector 25 at the zone of greatest light concentration, the projection of which normally gives the undesired blinding effects. The position of the shell 55 may be adjusted to meet various driving conditions, although its position as illustrated in Fig. 6 has been found to be most desirable in cutting off the reflection of light by substantially the lower half of the reflector.

For example, the direct rays emanating from the light source are cut off substantially on the 60 arc A as shown in Fig. 1. Substantially all of

the reflected rays B from the reflecting surface of the shell 5, together with the upwardly projected direct rays not coming within the arc A, strike the upper rear portion of the reflector 25 and are projected generally downwardly thereby. The rays C reflected downwardly from the mirror-like surface of the shell 5 and the downwardly projected direct rays not coming within the arc A are comparatively few and strike a small sector at the rear of the reflector 25 and 65 slightly below the bulb 6, from which they are projected fanwise to the front of the headlight.

While I have described my dimmer as being adjusted on the bulb to reflect the rays emanating from the bulb upwardly against the upper rear portion of the headlight, it will of course be understood that upon reversal of the dimmer the rays may be directed to any portion of the headlight as may be desired under the circumstances.

Having thus described my invention, I claim:

1. In combination with a light bulb having a plurality of adjacent annular grooves about the tip thereof and a plurality of annular ridges separating said grooves, a dimmer comprising a concave shell having a light reflective inner surface, a plurality of fingers attached to the shell at predetermined positions thereon and operative to hold the shell to the bulb in such position that a portion of the edge of said shell engages against one side of one of said ridges, said fingers conforming substantially to the contour of the bulb against which they are adapted to lie, a plurality of rivets attaching the fingers to the shell and having heads thereon adjacent the inner surface of the shell and spaced from the edge thereof whereby two of said heads seat in one groove of the bulb and the other heads seat in another groove thereby holding said shell in the position as aforesaid.

2. In combination with a light bulb having a plurality of adjacent annular grooves about the tip thereof and a plurality of annular ridges separating said grooves, a dimmer comprising a shell, a plurality of fingers associated with the shell at predetermined positions, a portion of the edge of said shell engaging a portion of one side of one of said ridges, and means on said shell coacting with the bulb to maintain the shell in adjusted position thereon, said means consisting of a plurality of projections on the inner surface of the shell and spaced from the edge thereof, certain of said projections seating in one groove on said bulb and the other projections seating in another groove thereon.

3. In combination with a light bulb having a plurality of adjacent annular grooves about the tip thereof and a plurality of annular ridges separating said grooves, a dimmer comprising a shell, a plurality of fingers formed integral with the shell and at predetermined positions whereby a portion of the edge of said shell engages a portion of one side of one of said ridges, and means on said shell coacting with the bulb to maintain the shell in adjusted position thereon, said means consisting of a plurality of projections formed on the inner surface of the shell and spaced from the edge thereof whereby two of said projections seat in one groove on said bulb and the other projections seat in another groove thereon.
